(57) **CLAIM**

The ornamental design for a computer screen with graphical user interface, as shown and described.

DESCRIPTION

FIG. 1 is a front view of a first embodiment of a computer screen with graphical user interface in accordance with the design;

FIG. 2 is a front view of a second embodiment thereof; and, FIG. 3 is a front view of a third embodiment thereof.

The outermost perimeter of broken lines depicts the computer screen or portion thereof and form no part of the claimed design. The internal broken lines show features of the computer screen with graphical user interface that form no part of the claim.

1 Claim, 3 Drawing Sheets
